Fig. 2

Fig. 3

Fig. 4

Fig. 5

Fig. 6

FIG. 1 is a perspective view showing the top, left side, and eyepieces of the binocular showing my new design; FIG. 2 is a top plan view of the binocular;

FIG. 3 is an elevation of the eyepiece end of the binocular taken on line 3-3 of FIG. 2;

FIG. 4 is a side view of the binocular taken on line 4-4 of FIG. 2;

FIG. 5 is an elevation showing the objective-lens end of the binocular and taken on line 5-5 of FIG. 2; and

FIG. 6 is a bottom plan view of the binocular taken on line 6-6 of FIG. 3.

I claim:

The ornamental design for a binocular, substantially as shown and described.
